UNITED STATES PATENT OFFICE

EDWIN A. RUTENBER, OF MILWAUKEE, WISCONSIN, ASSIGNOR TO A. J. LINDEMANN & HOVERSON COMPANY, OF MILWAUKEE, WISCONSIN, A CORPORATION OF WISCONSIN

CONVENIENCE OUTLET FOR ELECTRIC APPLIANCES

Application filed May 15, 1928. Serial No. 277,969.

The present improvements relate to electrical connections for use on electric ranges or other electrical apparatus.

A primary object of the present improvements is to provide a composite outlet connection for electric ranges, embodying means for receiving a fuse, as well as contact points for receiving the connecting plug of an electrical service article. A further object is the provision of a novel and convenient assembly unit which may be readily and firmly secured to a support, e. g., an electric range.

The present improvements further provide a convenient outlet unit combined with other essentials appurtenant thereto, which simplifies and eliminates a substantial amount of wiring heretofore necessary in electrical ranges and other apparatus of like character.

Other objects and advantages will be apparent to those skilled in the art upon reference to the accompanying specification and drawings in which—

Fig. 1 is a side elevation of a device embodying the present improvements;

Fig. 2 is an end elevation of the device illustrated in Fig. 1;

Fig. 3 is a view similar to Fig. 2, with cap removed;

Fig. 4 is a section on line 4—4 of Fig. 3;

Fig. 5 is a plan view of the inner face of the cap when removed;

Fig. 6 is a section on line 6—6 of Fig. 2;

Fig. 7 is a plan view of the porcelain base, showing line terminals, with screw collar removed;

Fig. 8 is a section on line 8—8 of Fig. 5.

The device embodying the present improvements is illustrated in assembled relation in Figs. 1 and 6, and is shown mounted on support 10 representing the wall of an electric range or other similar structure. As illustrated, the intermediate member comprises a porcelain base 11 with end members 12 and 13 attached thereto, as hereinafter described, also made of porcelain or other insulating material.

The base 11 has an axial bore 14 terminating in a shallow recess 15 on one face of said base and in a deeper recess 16 on the oppo-

site face thereof. On each side of recess 15, the face of base 11 is channelled to form grooves 17 to accommodate line wires 18 which are adapted for connection to line terminals 19 and 20, as illustrated. Seated in recess 15 is a screw threaded shell 21 of copper or other conducting material, having a mica or other insulating bottom lining 22, above which is disposed a contact member 23 connecting with terminal 19. Elements 22 and 23 are secured firmly to base 11 by means of screws 24 passing through bores therein. The heads of said screws rest in recesses 25 countersunk from recess 16, and are cemented therein against removal. The collar 13 is 55 interiorly screw-threaded and mounted on shell 21 as seen in Fig. 6. This cap or collar 13 accordingly insulates the shell from outside contact and also protects the terminals 60 for the line wires.

On that face of the base 11 having recess 16, and disposed in said recess, are a plurality of spaced contacts 26 and 27. Each contact comprises three projecting spring fingers 28, 29 and 30, two of which are opposed and the 65 third at right angles thereto as seen in Figs. 3 and 4. These fingers are adapted to receive and hold by frictional contact the prongs of the plug of some electrical appliance such as a lamp, iron or other service article.

Contacts 26 and 27 are held firmly in the illustrated position by screws 31 and 32, respectively, which also serve as conductors between the line terminals and said contacts. 70 As illustrated in Fig. 7, the link 33 lies in channel 34, below the plane of recess 15, and forms a connection between screw 32 and terminal 20, while screw 31 lies in contact with the underside of shell 21 to which it may be soldered, whence contact is made, through a fuse screwed therein, to line terminal 19.

The removable end member 12 comprises a cap for shielding and protecting the contacts 26 and 27 from outside contact. As seen 75 in Figs. 6 and 8, the cap 12 is provided with a protruding boss 35 having wells 36 and 37 for accommodating contacts 26 and 27, the latter being accessible through T-shaped apertures 36' and 37' in face 38 of cap 12. 80 85 90 95 100

A web 39 separates wells 36 and 37 and is provided with a bore 40 which is disposed axially of cap 12. A notch 41 is provided on the periphery of boss 35 as indicated and is adapted to receive a key 42 formed in the wall of recess 16 on base member 11. As seen in Figs. 3 and 6, an annular ridge 43 and key 44 are provided on the face of base 11 surrounding recess 16.

10 In assembling the structure illustrated, the support e. g. the wall 10 of an electric range is perforated at some convenient and accessible location, to provide a hole of sufficient size to receive ridge 43 of the base member 11, the periphery of said hole being also provided with a notch for receiving key 44 whereby relative movement of the base 11 with respect to the wall 10 is prevented. With the base 11 thus placed to the wall 10, with ridge 43 and key 44 protruding therethrough, the spring finger contacts 26 and 27 project through the hole. Cap 12, having leather washer 45 around the boss 35 thereof, is then inserted in the hole in wall 10 so that notch 41 is in register with key 42. The web 39 is slightly wider than the distance between spring fingers 30 of the contacts 26 and 27, which fingers accordingly grip the web and hold cap 12 in place. Upon 25 complete insertion of the cap, the boss 35 nests in recess 16, see Fig. 6, and the fingers 30 (through web 39) accordingly hold base 11 and cap 12 together, with wall 10 therebetween which latter supports same. This supporting function is supplemented, and base 11 and cap 12 secured against separation, by means of screw 46 which is inserted through bores 40 and 14, and secured in screw threaded engagement with an aperture in a keeper 47 disposed in recess 48 in element 11 and beneath the base of shell 21.

After the foregoing has been accomplished, line wires 18 are secured to terminals 19 and 20 and collar 13 is then screwed in place. A 25 fuse plug of any known design may now be screwed into shell or socket 21 and the organization is ready for use.

It frequently happens in employing an outlet of the character described that the appliances plugged in take more current than the line can withstand with the attendant "blowing" of a fuse. The replacement of such fuse usually is accompanied by great inconvenience and delay, due, among other reasons, 30 to lack of knowledge of its location as well as the remoteness thereof. However, the composite unit herein presented obviates all the foregoing disadvantages due to its accessibility and convenient location with respect to the outlet.

Furthermore, with the present improvements, a separate jack for the fuse and connecting wires from same to the outlet are eliminated. Applicant has accordingly devised a novel convenience outlet comprising

a single unitary structure embodying new features and a novel arrangement of parts, heretofore, so far as he is aware, not found in the art.

Various modifications of the organization 70 within the purview of the present improvements will be apparent to those familiar with the art and may be embodied without departing from the scope of the invention.

I claim.

1. A convenience outlet adapted to be used with electrical apparatus comprising a base having line terminals and a fuse socket on one face thereof, outlet contacts on another face thereof, a removable outlet cap adapted to secure said base to a support and a key member protruding from said last named face adapted to engage said support in interlocking relation. 75

2. A device of the character described comprising a porcelain base, line terminals, a fuse socket on one face of said base, a contact for each terminal on another face of said base, a removable collar for said socket and removable means guarding said contacts and cooperating to secure said base to a support. 80

3. An outlet assembly for electric stoves comprising a porcelain base having line terminals and a fuse socket on one face thereof, a projecting contact for each terminal on another face of said base, a removable shield for said contacts, all constructed and arranged so as to grip a stove wall between said base and shield, and means for securing said base and shield in said gripping relation. 85

4. A device of the character described comprising an intermediate base member and removable end members, line terminals and a fuse socket on one face of said intermediate member, a spring finger contact for each terminal on another face of said intermediate member, the arrangement being such that said end members guard said socket and fingers, said fingers holding one end member by frictional contact. 95

5. A device of the character described comprising a base member having line terminals and a fuse socket on one face thereof, a contact for each terminal on another face of said member comprising a plurality of spring fingers, a removable guard member having apertures adapted to receive said contacts, said guard member being held to said base member by fingers of each contact. 105

6. An electrical appliance comprising an insulated body member, line terminals on said member for receiving line wires, a threaded contact socket on one face of said member, a removable shield surrounding said socket and having threaded engagement therewith, spring finger contacts on another face of said member, a guard member for said contacts having perforations in which said contacts are disposed and securing means 115

between said guard and body member for holding said guard in position about said fingers and in association with said body member.

5 Witness my hand this 9th day of May, 1928,
county of Milwaukee, State of Wisconsin.

EDWIN A. RUTENBER.
